UNITED STATES PATENT OFFICE.

JOHN L. VAUGHN, OF SAN FRANCISCO, CALIFORNIA, ASSIGNOR OF ONE-HALF TO
CHARLES A. FEY, OF SAN FRANCISCO, CALIFORNIA.

AUTOMATIC TALKING-MACHINE.

1,274,980.

Specification of Letters Patent.

Patented Aug. 6, 1918.

Application filed October 16, 1916. Serial No. 125,787.

To all whom it may concern:

Be it known that I, JOHN L. VAUGHN, a citizen of the United States, residing at the city and county of San Francisco and State of California, have invented certain new and useful Improvements in Automatic Talking-Machines, of which the following is a specification.

The present invention relates to a phonograph and more particularly to a type of apparatus which is automatic in its operations after the depositing of a check or controlling coin therein.

The principal objects of the invention are to provide a construction wherein the operator may have at his disposal at all times the choice of playing any record associated with the apparatus; one wherein the records may be removed and replaced individually or may be removed or replaced as a single unit; one wherein the selected record is lifted from its support and is deposited on the rotatable supporting table when the apparatus is put into operation and is also lifted from the table and is returned to and is deposited on its support after the playing thereof, thus adapting the device to the playing of double faced disk records without injuring or scratching the under face of the selected record as removed from or returned to its support. To provide an apparatus having an improved needle feeding and discharging mechanism; one wherein the playing needles may be indiscriminately positioned in a suitable magazine, and will feed therefrom, one at a time, point downward; to provide an improved drive for the record supporting table wherein a uniform speed of the record table will be assured at all times; to provide an apparatus which is simple in construction and owing to its simplicity may be manufactured at a cost far below those now on the market which are designed to accomplish the same purpose, and one which is automatic in all of its operations after the depositing of the actuating coin or token. A further and important object of the invention is to provide a structure having a means for interrupting the operation of the mechanism on the failure

of the feeding of a new needle to the reproducer.

With the above mentioned and other objects in view, the invention consists in the novel construction and combination of parts hereinabove described, illustrated in the accompanying drawings, and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings forming a part of this application and wherein—

Figure 1 is a view in front elevation of a cabinet for mounting the preferred embodiment of my invention and provided with a transparent portion through which certain parts of the apparatus are visible.

Fig. 2 is a broken side elevation of the cabinet illustrating the sound box in vertical central section.

Fig. 3 is a vertical plan view of a portion of the sound box illustrated in Fig. 2.

Fig. 4 is a view in front elevation of the improved mechanism removed from the cabinet, with the parts thereof in normal position, and with a selecting mechanism adjusted to a position so that the top record or disk of the stack will be positioned on the table for playing on the next operation of the apparatus.

Fig. 5 is a sectional view taken on line 5—5 of Fig. 4, disclosing the means for moving the record engaging devices, and the trip mechanism for operating the same.

Fig. 6 is a detail broken sectional view taken on line 6—6 of Fig. 5.

Fig. 7 is a detailed sectional view taken on line 7—7 of Fig. 5.

Fig. 8 is a view in detail of the solenoid and the trip controlling means for the record engaging throw mechanism, viewed in the direction of the arrows on line 8—8 of Fig. 5 of the drawings.

Fig. 9 is a view in plan taken on line 10—

9-9 of Fig. 4 of the drawings, illustrating the means for moving a selected record into playing position and for returning the same to normal position on the completion of the 5 playing thereof.

Fig. 10 is a broken detailed plan view of one of the record carriers and its supporting frame.

Fig. 11 is a vertical sectional view of a 10 record carrier and associated parts taken on line 11 of Fig. 9.

Fig. 12 is a view in detail of the spring mechanism carried by one record carrier throw arms for delaying the movement 15 thereof until the record is engaged and lifted by the coöperating record engaging lever.

Fig. 13 is a detailed view in elevation, 20 partly in section, of the coin or token actuated switch mechanism associated with the coin or token guide.

Fig. 14 is a broken detailed view of the table and drive construction thereof.

Fig. 15 is a view in broken detail of the 25 reproducer, the needle clamp associated therewith and the needle discharge chute.

Fig. 16 is a view in detail of the needle discharge shifting and mounting means.

Fig. 17 is a detail view in side elevation of 30 the reproducer arm, the needle clamp controlling means carried thereby, and the switch controlling arms carried by the arm.

Fig. 18 is a view in plan of the mechanism 35 illustrated in Fig. 17.

Fig. 19 is a detailed view in side elevation of the needle magazine.

Fig. 20 is a view in side elevation of the needle magazine partly in section, illustrating the movable controlling slide.

Fig. 21 is a view in plan of the controlling 40 slide taken on line 21-21 of Fig. 20, with the opening of the slide in register with the chute outlet opening.

Fig. 22 is a transverse sectional view of 45 the needle magazine taken on line 22-22 of Fig. 19.

Fig. 23 is a view in perspective of the mechanism for gently lowering the reproducer in coöperative relation with the positioned disk and for returning the same to 50 normal position after the playing of the record.

Fig. 24 is a detailed view in elevation of the means for adjustably supporting a record container.

Fig. 25 is a view in detail of the record container, and the means for locking the same in its selected adjusted position.

Fig. 26 is a view in detail of the motor 60 controlling switch and associated mechanism.

Fig. 27 is a view of the wire diagram.

Referring more particularly to the accompanying drawings, wherein like characters

of reference designate corresponding parts, 65 1 indicates a suitable cabinet for protecting and housing my improved mechanism, and the same is provided in the upper portion of its front wall with an opening 2, through which certain parts of the mechanism are 70 visible, and said opening is preferably covered or protected by a glass 3. A dividing wall 4 extends across the upper portion of the cabinet and provides a chamber 5, which opens at the front of the cabinet and is preferably covered by a fine mesh screen 6. A sounding board 7 extends the full width of chamber 5, and the same rests at its rear edge on the rear edge of the wall 4, and curves upwardly with its forward edge adjacent the 80 front of the chamber, as in Fig. 2 of the drawings. A suitable opening 8 is provided at the center of the dividing wall 4, and extending from each side thereof, are the diverging sound box side walls 9. 85

Mounted within the cabinet is a suitable supporting frame consisting of the vertical members 10 and the top and bottom members 11. A disk supporting table 12, is positioned within the cabinet in rear of the 90 opening 2 and is mounted on the upper end of the shaft 13, resting at its base in a bearing 14 which rotatably mounts the same and which is carried by the supporting arm 15, projecting from one of the vertical members 95 10. The shaft 13 extends through an arm 16 extended from one of the members, said arm maintaining the same in a vertical position.

The table is rotated at a constant speed 100 by the following mechanism, particular attention being directed to Figs. 4 and 14 of the drawings. Rotatable on the shaft 13 are the friction drive and driven disks 16' and 17, and positioned between the same is a 105 suitable felt or other fabric friction surface 18. A spring 19 interposed between the under face of the disk 16 and a collar 20 on the shaft 13, forces the drive disk 16 upwardly in frictional contact with the surface 110 18, and through said surface drives the disk 17. A peripheral groove 21 is formed in the disk 16 and in the same operates a drive belt 22 passing over the guiding rollers 23 and driven by a driven pulley on a shaft 25 115 mounted in bearings 26, and which is in turn driven by a belt 27 passing over a drive pulley 28 and operated by a suitable motor 29 which receives its power through the leads 29' from an electrical source 30. A suitable governor 120 31 of the well known type is carried by the arm 15, and is in geared relation with the shaft 13, and the same limits, according to its adjustment, the maximum speed of the driven disk 16'. It will be apparent by 125 driving the table 12 through the friction disks 16' and 17, fluctuations in the speed thereof is overcome, as the frictional con-

tact between the drive and driven disks is the same at all times.

The records to be positioned on the table by a hereinafter described mechanism are carried in the following manner, attention being directed to Figs. 4, 9, 24 and 25 of the drawings.

Suitable vertically disposed guide rails 32 are positioned within the cabinet adjacent one side thereof, and on the same operate the guide rollers 33 carried by the upper end of a vertically movable supporting frame 34 which is formed with the horizontally disposed base portion 35. Suitable weights 36 carried at one end of chains 37, passing over the two supporting gears 38 and secured at their opposite ends to the frame 34 enable the frame 34 to be adjusted relatively to the guides 32 and to be retained in its adjusted position by the counter-balancing weights 36. The frame 34 is capable of adjustment to properly position the selected record for movement to the table 12, by a suitable handle 39 at the front of the cabinet 1, and which is carried by a rotatable shaft 40 extending within the cabinet and mounting a gear 41 which intermeshes with a gear 42 coöperating with one of the gears 38. The rotation of the shaft 40 causes a corresponding rotation of the gears 38 which raises or lowers the frame 34. The records 43 are carried in a horizontal position in spaced relation, one above the other in a suitable magazine or holder 44 comprising the looped frame, the horizontal portion 45 of which rests on the base portion 35 of the frame 34. Suitable substantially U-shaped horizontally disposed record supporting frames 46 are secured at one side to the vertical portion 47 of the holder 44 and are slightly spaced one above the other as in Fig. 25 of the drawings. The frames each carry a plate 48 on which rests one of the records 43, they being centered on their respective frames by suitable centering pins 49, one of which projects upwardly through the central opening 50 in the respective records. A suitable pawl 51 pivotally mounted at one end to the frame 44 and forked at its free end is adapted to be moved into engagement with a pin 52 on the portion 47 of the holder 44, and to lock the same in position on the holder with the pin 53 at the base thereof, received in the centering hole 54 in the horizontal base portion 35 of the frame 34. A locking frame 51' pivoted in bearings 51² on one of the guides 32 may be swung into the path of the frame 34 to limit the downward movement of the frame or to lock the frame in its lowermost position within the cabinet and prevent the raising thereof.

Simultaneously movable with the raising and lowering of the vertical movable frame

34 to indicate the record selected for placing on the table 12, is a pointer or other indicating means 54, which operates over a suitable index frame 55 in which are removably positioned index cards 56 of the respective records in the holder 44. The cards 56 are arranged in the same order as the records are positioned in the holder 44 and the pointer 54 is adapted to move over the face thereof to indicate the record in position to be transferred to the table 12 by a suitable flexible connection 57 secured thereto and which passes over a roller 58 in geared relation with one of the cogs 38. A weight 59 counterbalances the pointer 54 and said pointer operates on a guide rod 60 adjacent the holder 55, Fig. 4 of the drawings.

The mechanism for engaging, lifting and moving the selected record from its support and for positioning the same on the table 12 for the playing thereof, and for lifting and returning the record after playing to its support is more fully illustrated in Figs. 4, 9, 10, 11 and 12 of the drawings, and operates in the following manner.

Supporting and guide rails 61 are secured at their ends to the uprights 10 and extend transversely of the frame in a plane approximately level with the top surface of the table 12, and slidably mounted on each of said rails is a carrier, said carriers being adapted to be operated in unison at opposite sides of the record. Each carrier comprises a face plate 62 positioned at the outer side of the rail and a top plate 63 projecting inwardly a slight distance over the top thereof. The base of the guide plate operates on a guide rail 64 and the upper portion thereof carries guide rollers 65 at each side thereof for operating in contact with the outer side face of guide rail 61, and also carries a supporting flange 66 adjacent each roll for resting on and supporting said carrier on the rail 61.

Pivotedly mounted on the top plate 63, as at 67, are the levers 68 carrying at their ends the downwardly extending engaging fingers 69 for movement beneath a disk or record to raise and lower the same, as hereinafter described. A lever operating plate 70 is movably mounted beneath the top plate 63 and is slotted at its opposite ends, as at 71, to receive the pins 72 carried by the lever 68 at a point beyond their pivotal support 67, and said plate is yieldably supported at its base by a flat spring 73 secured to a member 74 attached to the inner surface of the face plate 62 adjacent its lower end. The tendency of said spring is to draw said plate 70 inwardly and to force the ends of arms 68 away from each other and from beneath a record 12.

A forked lug 75 is carried by the vertical portion 76 of the plate 70, and coöperating

with the same is the movable upper end of an arm 77, pivoted at its base, as at 78, to the inner face of the plate 62. A link 79 pivotally connects the arms 77 with the upper end of a carrier moving lever 80 pivotally supported at its base as at 81.

A cam track 82 extends longitudinally of a portion of the inner face of each rail 61, and over the same is adapted to ride an anti-friction roller 83 at the upper end of arm 77.

To insure the inward movement of the levers 68 to lift the selected record either from its pin 49 on its seat or from the centering pin on the table 12 prior to the carrying of the same from one to the other, a suitable forked spring is carried as at 84 on the upper face of the plate 62 and the forked branches 84' and 84² thereof are curved at their upper ends as at 85 and 85' and project beyond the rear of the plate through arculate slots 86 and 86', one at each side of the arm 77.

During the initial movement of the arm 77 by lever 80, when the parts are in a position as in Figs. 10, 11 and 12 of the drawings, the roller 83 rides upwardly on the beveled end 87 of the track 82, forcing the plate 70 outwardly to cause the arms 68 to be moved toward each other to engage a disk 30 and lift the same vertically. During this movement of the arm 77, the fork 84 of the spring has exerted pressure against the side of said arm opposite to the intended movement of the carrier and the tension of said 35 spring causes a retarding force on the carrier in the direction of the arrows—Fig. 12, to prevent the movement thereof on the guide rail until the record is engaged. The retardation is exerted until such time as the 40 arm 77 has passed the inner end of the slot 86 and the action of the spring is arrested owing to contact with the inner end of said slot.

At the completion of the movement of the 45 carrier in either direction, the same is first arrested by contact with the limiting lug 88 and then the levers 68 are permitted to be moved upwardly by the action of the spring 73 to release the engaged record. This is 50 accomplished by the spring arms 84 and 84', the tension thereof being sufficient to resist the strain of moving the carrier without bending and until the carrier contacts with one of the lugs 88, at which time the further 55 movement of the link 79 operates the arm 77 to overcome the tension of the spring and rides on one beveled side of the forked lug 75 to force the plate 70 outwardly.

To simultaneously operate the carriages to 60 position a selected record on the table for the playing thereof and for returning the same to its place of deposit, the following mechanism is employed, attention being directed to Figs. 4, 5, 6, 7 and 8 of the drawings.

The levers 80 are connected through links 89 to the cranks 90 carried by the rods of a rotary shaft 91 mounted in the supports 92 resting on a bracket on the platform 93 supported by certain of the uprights 10.

The shaft 91 loosely mounts a gear 94 which intermeshes with and is driven by a pinion 95 carried by a rotatably mounted shaft 96, driven through a belt connection 97 operating over a grooved pulley 98 on the shaft 96, and a pulley on the shaft 25.

Mounted to rotate with the shaft 91 is a plate 99 carrying on its end the curved pawl 100 pivotally mounted within its length, as at 101, and provided on the end in its direction of travel with a hook 102 which is adapted when the rear end of the pawl is released, in a hereinafter described manner, to be drawn by the spring 103 within the path of the pins 104 on the gear 94 and to be moved thereby so that the gear 94 and shaft 91 will be locked to move simultaneously a one-half revolution. Each one-half revolution of the shaft 91 moves the carriers their full distance in one direction on the guides 61.

To permit a period of rest for the carrier during the playing of each record, the following mechanism is employed, reference being had to Figs. 5, 6, 7 and 8 of the drawings. Extending transversely of the shaft 91, adjacent the face of the gear 94 mounting the pins 104, is a substantially rectangular frame, the base 105 of which is pivotally mounted in bearings 106 on the arm 93. The base 105 carries at its end the upwardly projecting trip arms 107, each carrying an outwardly projecting trip pin 108, which are adapted to normally lie within the path of movement of the rear end of the pawl 100 and to normally maintain the hooked end of the same from engagement with one of the pins 104.

A spring 109 maintains the trip arms 107 and pins 108 in their normal position, as in Fig. 8, and to momentarily actuate the trip arms in unison a suitable solenoid 110 is provided, the same being connected to one of the arms 107 by a link 111, as in Fig. 8 of the drawings. The solenoid is connected to the battery 30 through leads 112 and 113 into which cut the motor circuit 29' and the solenoid is initially operated through a coin actuated switch 114. On the closing of the switch 114 the solenoid 110 is momentarily energized to overcome the tension of spring 109 and to draw the arms 107 rearwardly to release the pin 108 from the rear of the pawl 100, permitting the spring 103 thereof to throw the hook 102 within the path of travel of the pin 104. During the rearward movement, one of the arms 107 strikes the pin 115 of the motor controlling switch blade 116, Fig. 26 of the drawings, which closes the circuit between 110 115 120 125 130

the leads 29' and permits the operation of the motor 29.

The blade is pivoted, as at 117, to a base 118 which carries spaced contacts 119, one 5 of which is carried by each lead 29' and said switch blade is locked in closed position by an arm 120 of the locking frame 121 pivotally mounted in bearings on the base 118 and normally forced inwardly by the 10 spring 122.

The operation of the motor rotates the pinion 95 and gear 94, and during the movement of said gear in the direction of the arrow—Fig. 6, one of the pins 104 engages 15 the hooked end 102 of the pawl 100 and causes the shaft 91 and gear 94 to rotate in unison to operate the carriers to position the selected record on the table 12. After a one-half revolution of the plate 99 with 20 the shaft 91, which is sufficient to operate the carriers to position the selected record on the table 12, the rear end of the pawl 100 in its travel engages the opposite pin 108, thereby disengaging the pawl 100 from its 25 coöperating pin 104 and permitting the carriers to remain at a point of rest during the playing of the positioned record.

A reproducer 124 carried by the arm 125, Figs. 4, 15, 17, 18 and 27 of the drawings, 30 coacts with the positioned record in the playing of the same, and said reproducer supports and carries a spring finger 126 at the rear end thereof, which is adapted, after the reproducer has traveled inwardly over the 35 face of the positioned record to play the same, to engage and force together the spring contacts 127 and 128 in leads 129 and 130, which connect with the leads 112 and 113, Fig. 27 of the drawings.

40 The completing of the circuit through the leads 129 and 130 again energizes the solenoid 110 which operates the frame 107 to withdraw the pin 108 from in rear of the pawl 100 and to permit the pawl and plate 45 99 to rotate a one-half revolution with gear 94 and permit the played record to be moved from the table 12 and carried by the carriers to its normal place of deposit.

On the return of the record to its normal 50 place of deposit, the pin 131, Figs. 5 and 26 of the drawings, carried by one of the cranks 90 engages the curved free end 132 of the frame 121 and actuates the same in the direction of the arrow, Fig. 26, with- 55 drawing the arm 120 from the blade 116, and permitting the spring 133 to operate the blade 116 to break the motor circuit through leads 29' and stop the motor.

It will be apparent that the solenoid is 60 operated immediately on the depositing of a controlling coin or token and during its initial operation closes the motor circuit, which remains closed during the position- 65 ing of the selected record on the table 12, the playing of the record, and the return of the

same to its place of deposit. The solenoid is again operated after the completion of the playing of the record, due to the movement of the arm 125, but this operation does not effect the motor circuit, the motor circuit remaining closed until the pin 131 on one of the cranks 90 releases the motor control switch blade 116.

During the positioning of the selected record on the table 12, a new needle is de- 75 posited in the needle holder of the reproducer, the mechanism for accomplishing this purpose being clearly illustrated in Figs. 7, 15, 16, 17, 18 and 19 to 22 inclusive of the drawings.

The reproducer 124 is of the usual disk form provided with the usual diaphragm 135, co-acting with the center of which is an arm 136 extending from the inner end of the T-shaped needle holder 137 carried at 85 the lower peripheral edge of the reproducer by the lugs 138. The arm of the needle holder 137 is centrally bored, as at 139 to permit the passage of the needle there- 90 through, and said main arm is recessed or notched as at 140 to permit the curved lower portion 141 of a needle clamp to be received therein and engage the needle positioned within the holder and retain the same there- 95 in. The needle clamp is pivotally mounted as at 143 to the arm 137 at right angles to the pivotal mounting of said holder and the lower portion 131 thereof is normally forced into said recesses 140 by a coiled spring 144. Carried by the shaft 91, Fig. 100 17 of the drawings, is a cam 145 on the peripheral edge of which is adapted to ride the pin 146 on a vertically disposed rod 147 pivoting on a vertical axis, and said rod carries an arm 148 at its upper end which 105 coacts through a link 149 with the upper end of a lever 150. The lever is pivoted within its length, as at 151, to a bracket 152, extending from the base of the amplifying horn 153 which projects upwardly 110 through the opening 8 into the chamber 5 and to said horn the reproducer arm 125 is connected by a coupling 154, which permits a vertical and horizontal movement of the outer end of the reproducer arm. The lower 115 end of the lever 150 is provided with angularly disposed portion 155' which is adapted when the reproducer arm 125 is in non- playing position, as in Fig. 18 of the drawings, to be received in the looped end of a 120 horizontally disposed trigger rod 156, the front hooked end 157 of which rests on and coöperates with the upper end 158 of the needle clamp. The inner terminal end of the trigger 156 is looped as at 156' and in 125 the same operates a supporting arm 156² carried by the reproducer supporting arm 125. The terminal spring portion 156³ of said trigger operates to normally force said trigger forwardly to permit the clamp 142 130

- to lie in closed position when the reproducer arm is moved toward the selected record, and the rear end of said trigger is moved from without the path of the hooked portion 155'.
 The needles 155 to be fed to the needle holder on the reproducer are carried within a suitable magazine 160 with their pointed ends toward either end of said magazine.
 10 The feed opening of the magazine through which the needles are inserted to lie one on another, as in Fig. 20 of the drawings, is adapted to be closed by a suitable cover 161 held in position by a substantially U-shaped member 162, and reciprocating beneath the open bottom of the magazine and providing a bottom therefor, is a needle feed slide 163, resting upon a supporting plate 164. A frame 165 connects with the sides of the plate 164 and extends over the slide 163, guiding the same in its reciprocation. A needle feed opening 166 extends transversely of the slide 163 and is of sufficient size to admit of the reception of but one needle at a time, as in Fig. 20 of the drawings, when the opening is in register with open bottom of the magazine. To insure the discharge of the needles 155, point downwardly, through the chute 167 which extends downwardly from the underside of the supporting plate 164, said plate is provided in line with the upper end of said chute and at one side of said magazine with a transversely extending groove 168, below which is a directing opening 169 with which the feeding opening 166 in slide 163 is adapted to register on each forward reciprocation of the slide. The directing opening 169 is of a length less than that of the needles, and at its opposite ends has the contracted tapering portions 170, as in Fig. 21 of the drawings, through which the points of the needles 155 pass when disposed in either direction. This construction insures the needles passing point downwardly into the chute 167 as the bases thereof project beyond the end of the directing opening 169, as in Fig. 21 of the drawings.
 To reciprocate the feed slide 163 immediately prior to the positioning by the carriers of the selected record on the table 12, to position a new needle 155 in the holder 137, a link 171, Figs. 4 and 20 of the drawings, pivotally connects at one end, as at 172, with the slide and at its opposite end with the upper end of a lever 173, pivoted within its length as at 174 and curved at its lower end as at 176, Fig. 7 of the drawings. The curved end 176 lies within the path of movement of the actuating pin 177, Figs. 5 and 7 of the drawings, carried by a disk 178 on the shaft 91. Immediately after the operation of the motor on the initial operation of the device, the rotation of the shaft 91 causes the pin 177 to coact with the lower end of lever 173, pressing the same outwardly and causing the needle 155, received in the opening in said slide, to be moved from the magazine and drop point first through the chute 167. A spring 167' resets the slide 163 to its normal position, as in Fig. 20, immediately after its actuation. During the operation of the magazine to feed a new needle, the reproducer is directly below the chute 167 thereof, it having been swung there by the operation of the following mechanism immediately after the playing of the last record.
 The reproducer carrying arm 125 is provided at its outer end with a bracket 178 mounting an idler 179 which operates on a suitable curved guide arm 180 forming one end of a frame, the main member 181 of which is disposed horizontally and is mounted in bearings 182. The opposite arm 183 of the frame is disposed at substantially right angles to the main member and connects at its end through a link 184 with the crank 185 of the shaft 186 of a suitable clock work 187. The shaft 186 carries a ratchet 188 coöperating with which is a pawl 189 carried by a gear 190; this construction enabling a free upward movement of the crank 185 during the lifting of the reproducer from the record without the actuating of the clock work and a slow downward movement of the reproducer when lowered on a positioned record.
 A lug 190¹ is carried by the arm 180 and the same limits the inward movement of the idler 179 on the arm 180 and positions the reproducer arm at one side of the table 12 for the discharge of the used needle and to receive a new needle on the playing of a succeeding record.
 The arm 180 is raised to lift the arm 125 and cause a movement of the reproducer to one side of the record after the playing of the same, through the actuation of the lever 190² pivotally connected at one end to the arm 183, Fig. 23 of the drawings. The lower end of the lever coacts with one end of a link 190³ pivotally connected at its opposite end with a support 190⁴, Fig. 7, and said link carries a pin 190⁵ for coöperating with the depressions 190⁶ arranged at diametrically opposite sides of the periphery of the disk 178 rotatable with the shaft 91. One of said depressions lies beneath the pin 190⁵, during each period of rest of the carrier moving levers 80 to permit the dropping of the link 190³ and the lowering of the reproducer 124 onto the record. The link 190² carries a pin 190⁸ which coöperates with a retaining lug 190⁹ on a pivoted supporting lever 191¹ carried by a support 191². The curved end of the lever 191¹ lies within the path of travel of one of the carrier mov-

ing levers 80 and is adapted to be engaged and actuated thereby when said lever is at the end of its travel in a direction to position a record on the table 12. A spring 191⁵ moves the lever 191¹ to normal position on the disengagement of the lever 80 from the end thereof, and maintains the lug 190⁹ beneath the pin 190⁸ after the pin has been elevated during the raising of the reproducer from the record by the pin 190⁵ riding on the periphery of the disk 178.

The needle 155 as it leaves the chute 167 is deposited point downward into the upper flared end of the needle guide 191, Figs. 4 15 and 15 of the drawings, carried on the reproducer 124, and the lower end of said guide co-operates with the upper end of the bore 138 and guides the needle thereinto. At the time of the feeding of the needle 20 to the chute 167; the arm 125 is in its position at one side of the table 12 with the top of the guide 191 in alignment with the chute 167 and the clamp 142 in its raised position, as in Fig. 15 of the drawings.

25 An open ended tubular needle discharge 192 is supported within its length by a bracket 193 pivotally mounted as at 193¹ to a support 194. A needle rest 195 is pivotally mounted as at 196 to the upper end of 30 the discharge 192 and is yieldably held in a plane parallel to the upper end of the discharge by a spring 197. The discharge 192 is oscillated on its pivot by the following mechanism to position the same in line with 35 the bore 139 to receive the used needle released therefrom on the raising of the clamp 142, and carry the same to a place of deposit, and to position the rest in line with the bore when a new needle is fed thereinto, 40 to prevent the passing of the needle therethrough and to retain the needle in position in the bore until the clamp 142 is released.

The bracket 193, Figs. 16 and 17 of the drawings, carries spaced upper and lower 45 arms 198 and 199, and adapted to co-operate with the free ends of each is an actuating pin 200 carried by a disk 201 secured to the shaft 91 and rotatable therewith in the direction of the arrows. The rotation of the disk 201 causes the pin 200 to first contact with the bevelled end 202 of the lower arm 199 which 50 action tilts the discharge 192 on its pivot 193 and positions the rest 195 beneath the bore 139 to receive the end of the needle. 55 On the completion of approximately a one-half revolution of the disk 201 the pin 200 contacts with the upper arm 198, causing the discharge 192 to tilt forwardly, as in Fig. 15 of the drawings, to receive the used needle 60 as released from the holder 137. A spring 203 carried by a plate 204 through which the upper end of the discharge 192 extends, bears against the wall of the discharge and retains the same in its tilted position. A spring 197 is

of such tension as to readily yield to the 65 weight of the reproducer 124 and the arm 125 when the same are permitted to slowly lower on the actuation of the lever 191¹.

Should a needle fail to feed to the reproducer immediately prior to the positioning 70 thereof on the record to be played, the absence of the needle in the bore 139 will permit the reproducer to drop onto the record, so in order to stop the operation of the motor, to prevent injury of the record, a 75 contact finger 204, Figs. 17, 18 and 27 of the drawings, is provided at the rear of the arm 125, and the same is adapted to connect the contacts 127 and 128 to short circuit the motor should the reproducer be lowered on 80 the record without a needle.

To lock the record holder in its adjusted position, after the starting of the motor, the following mechanism is provided, attention being directed to Figs. 4, 9, 16 and 25 of 85 the drawings.

A lever 205 is pivotally mounted at the side of one of the guides 32 to rotate on a vertical axis in bearings 206 and the curved upper end of the same carries a wedge locking lug 207, which is adapted for moving to a position between the projecting ends 207¹ of the frames 46 and to lock the holder in its vertical adjusted position. The lower curved end 208 of the lever is connected 90 through a link 209 with a lever 210 pivotally supported at its end as at 211 on the support 93. The lever 210 is provided within its length with a pin 212 which is adapted, when the carrier is in co-operative position 100 with the record holder, to lie in a groove or recess 213 in the peripheral edge of the disk 201, and on the movement of the carriers said pin is adapted to be forced out of the recess 213 against the tension of the spring 105 214 and to contact with and ride on the peripheral edge of disk 201, which will throw the lug 207 to locked position between the projecting ends of the frame 46.

The starting of the mechanism is preferably controlled by the depositing of a coin or token in the coin chute 215 positioned within the cabinet 1 and the upper end 216 of which projects through the cabinet front wall, as in Fig. 4 of the drawings.

110 The chute 215 is cut out within its length, as at 217, Figs. 4 and 13 of the drawings, and in said cut out is adapted to be received by the coin retaining lug 218 on one of the carrier shifting levers 80. The lug 218 is 115 adapted, when the levers 80 are in their normal position, to co-operate with a corresponding lug 219 on one of the contact fingers of the switch 114. The lugs will retain the operating coin or token suspended 120 within the tube a sufficient time to enable the motor circuit to be closed and the various mechanisms to be put in motion, at 125

which time the movement of the lever 80 will withdraw the lug 218 and permit the coin to drop from the chute into the receptacle 220.

- 5 A retaining pin 221 carried by a lever 222 pivotally mounted as at 223 beneath the disk 178, is maintained in contact with the periphery of said disk by a spring 224 and said pin is adapted for coöperation with the 10 recesses 190⁸ and to be received in one of the same to frictionally retain the shaft 91 in its rotated position on each period of rest of the record carriers.

The parts being in a position as in Fig. 4 15 of the drawings, the operation of the device is as follows:—

- The handle 40 is operated until the indicator 54 points to the index of the desired record to be played and which is correspondingly moved into coöperative relation 20 with the carriers on the registering of the indicator with the proper card. A controlling coin or token is now deposited at 216 and the same makes a circuit through the 25 switch 114 and solenoid 110 which closes the switch 116 operating the motor 29. The momentary operation of the solenoid permits the lug 102 to fall within the path of the pins 104, enabling the shaft 91 and gear 30 94 to rotate in unison for a one-half revolution in the direction of the arrows, Fig. 6. During the rotation of the shaft, the selected record 43 is lifted from its centering pin 49 by the movement of the fingers 69 beneath 35 the same, and the raised or lifted record is moved by the carrier levers 80 to a position over the table 12 and is deposited thereon. As the record is deposited on the table 12, the rear end of the catch 100 has completed 40 a one-half revolution with the shaft 91 and is in contact with one of the pins 108 which disengages the hooked end 102 thereof from its coöperating pin 104 at which time the carriers are permitted to remain stationary. 45 Immediately prior to the depositing of the record on the table, a new stylus or needle 155 is fed, point downwardly, to the holder 157, and strikes the rest 195 as the same has been moved beneath the bore 139 by its operating mechanism. The needle is now retained in the holder by the operation of the clamp 141, Fig. 15, which is released 50 through the continued operation of the shaft 91. After the needle is fed to the holder 157, one of the levers 80 contacts with and operates with the lever 191 permitting the reproducer 124, which has been in starting position, to slowly lower onto the positioned rotating record, through the action of the 55 clock work 187. Immediately after the selected record is removed from the carrier 34, said carrier is locked in its adjusted position by the lug 207. The record is now played and as the needle has completed its 60

movement inwardly over the face thereof, during the playing of the record, the finger 126 engages the contact 128 and again actuates the solenoid 110 which again permits the hooked end 102 of the catch 100 to engage another of the pins 104 on the gear 94, causing a simultaneous one-half revolution of the shaft 91 and gear 94, during which time the reproducer is first lifted from the record and returned to normal starting position, due to the operation of the disk 118. The record is then lifted from the table 12 and is returned to and lowered onto its support by the action of the carriers, and about this time the finger 131 engages the switch release 132, Fig. 26 of the drawings, to release the switch and break the motor circuit which stops the operation of the mechanism until such time as another coin is deposited.

Having thus described my invention, what I claim as new and desire to protect by Letters Patent is:—

1. In a talking machine, the combination with a reproducer, a horizontal turn-table and motor mechanism, said turn-table provided with a record centering pin for passing through an opening in the center of the record when the same is positioned thereon, a magazine for disk records vertically movable to bring any one of the records therein opposite the turn-table, said magazine provided with record centering pins, a carrier including a plurality of arms one pair positioned at opposite sides of the record and each having a downwardly inclined portion for engaging beneath the selected record to move the same vertically relatively to said centering pins, means for operating said carrier to move the record engaged thereby to and from the magazine and into and out of position on the table, and means for vertically moving said magazine and mechanism for engaging said magazine for locking the same.

2. In an automatically operated token controlled talking machine, the combination with a turn table for disk records, driving mechanism for said turn table, a reproducer arm mounted to shift both horizontally and vertically, a sound box on said arm, carriers for automatically moving records into and out of operative position upon said turn table, means for positioning a selected record into operative position relatively to said carriers, and mechanism for rapidly raising and slowly lowering said arm and for moving the same to starting position, the same including a curved arm coöperating with the sound arm and fulcrumed at one end for vertically swinging movement, a cam for raising said arm, and an escapement for regulating the lowering of said arm.

3. In a talking machine, the combination with a turn table for rotating the disk rec-

ords and provided with a centering pin, a coöperating sound-box, a record magazine for supporting a plurality of records in spaced superimposed relation, said magazine provided with centering pins for centering the records in position thereon, means for raising and lowering the magazine to select a record, an automatic carrier mechanism for raising the selected record from its centering pin in said magazine and for moving the same horizontally to a position over said turn table and for depositing the same on said turn table with the centering pin of said turn table through the aperture in the record.

4. In a talking machine, the combination with a reproducer, a turn table provided with a record centering pin and an operating mechanism, a magazine arranged to support a plurality of disk records in super-

imposed supported relation at one side of said turn table, a fixed centering pin on each record support and adapted for extending through the centering openings in the respective records, means for moving said magazine for bringing any one of the records therein in line with said turn table, and a carrier mechanism for first raising the record from its centering pin, carrying the same to its place of deposit, and lowering said carried record onto its support with the centering pin projecting through the central opening therein.

In testimony whereof I have signed my name to this specification in the presence of two subscribing witnesses.

JOHN L. VAUGHN.
